UNITED STATES PATENT OFFICE.

WILLARD C. JAMES, OF LOS ANGELES, CALIFORNIA, ASSIGNOR TO FRANK L. BELKNAP,
OF CHICAGO, ILLINOIS.

SCREENED BED HAVING VERTICAL PIVOTS.

1,353,163.

Specification of Letters Patent. Patented Sept. 21, 1920.

Application filed November 20, 1913, Serial No. 802,169. Renewed February 20, 1920. Serial No. 360,071.

To all whom it may concern:

Be it known that I, WILLARD C. JAMES, a citizen of the United States, residing at Los Angeles, in the county of Los Angeles and State of California, have invented a new and useful Screened Bed Having Vertical Pivots, of which the following is a specification.

This invention relates to structures of the class shown in my previous applications for Letters Patent of the United States for wall beds, Serial No. 722112, filed September 24, 1912; Serial Nos. 727608 and 727609, filed October 12, 1912; and masked bed, Serial No. 771545, filed June 3, 1913, in which I have shown various constructions comprising the combination with a pivotal support, of a bed frame and connections between the bed frame and support for permitting both rectilinear and rotary movement of the frame relative to the support in a substantially horizontal plane, it being designed that the handling of the bed can be thereby accomplished with greater ease and with greater freedom of movement than with other bed constructions.

Objects of the invention are to increase the convenience of storing the bedstead; to increase the ease of moving the storable bedstead from stored position to position for use, and vice versa; to make provision for storing the bedstead more completely out of the way by means that are less obtrusive and less in the way than those hereinafore provided; to provide for use of the bedstead on either side of the storage chamber so that at any time, as during fair or otherwise agreeable weather, the bedstead may be swung from storage position in its closet into position for use on a sleeping porch on one side of the closet, and at any time desirable, may be swung into position inside a room on the other side of the closet; the opposite walls and the doors of said closet constituting the means for concealing the bedstead when not in use.

In carrying out this invention provision is made whereby the bedstead is permanently pivoted inside a closet to top and bottom supports at a considerable distance away from the opening or door-jamb of

the closet or storage chamber, so as to avoid various objections arising from pivoting the bedstead on a pivotal support permanently fixed in, near to or adjacent such opening. 55

In said previous inventions I employ jointed members comprising primary and secondary arms, the primary arms being pivoted to the bedstead and the secondary arms being pivotally mounted near the opening of the storage chamber.

By this new construction it is designed to make provision whereby the handling of the bedstead outside the closet may be effected in a minimized space, and whereby greater amplitude of movement inside the storage space may be afforded; and whereby the length of the swinging arms may be materially reduced for any given depth to which the bedstead is to be inserted into the storage chamber and it is made possible to so mount the bedstead and to so arrange it in combination with the structural elements, as the closet or chamber walls and doorways and doors, that when one takes hold of a part of the bed frame or bedstead to move it, pressure on the bedstead will cause it to move in the direction of such pressure. That is to say, an object of the invention in part is to avoid liability of encountering dead centers in the operation of the bed so that a novice can easily move the bedstead from and restore it to concealed position. 75

In this invention I still employ the jointed members comprising primary and secondary arms, the primary arms being pivoted to the bedstead as before; but in contradistinction to said previous inventions, I have now conceived of and produced a novel construction wherein the pivotal mounting of the secondary arms can readily be located at considerable distance, say, two feet, more or less, from the opening of the storage chamber, thus avoiding certain objections present with and securing certain advantages absent from prior storable beds. 95

A distinction between my former conceptions as disclosed in said former applications and my conception herewith disclosed is that in the former inventions I provided the secondary arms with elbows, so that said secondary arms could be extended around the 100

door-jamb when the bedstead is out of the storage chamber, whereas in this invention I provide the primary arms with elbows so that said primary arms can be extended 5 around the door-jamb.

In this connection it is noted that I term the arms next to the bed, the primary arms, that such arms primarily support the bed and are supported in turn by one or more 10 arms, the number and construction of which are varied, to accommodate the bed to various arrangements of sleeping apartments.

In this invention both primary and secondary arms are made of especial importance in swinging the bedstead far into the 15 storage space, but are of value also when the bedstead is out of storage.

A feature of this invention in its full development is the provision therein of a 20 storage chamber having two openings and provision for swinging the bedstead through one or the other of said openings along either the front or rear side walls of the storage chamber in one case or the other as 25 desired.

To effect the foregoing I have conceived of providing a carrier device having a jointed member composed of three arms and the construction is such that the primary 30 and secondary arms can be used alone the same as a two-armed member when it is desired to swing the bedstead through one of said openings, the tertiary arm being thrown into commission when it is desired 35 to swing the bedstead through the other of said openings or when it is desired to swing the bedstead edgewise farther into the storage chamber.

It is noted that by thus being able to 40 swing the bedstead out of the storage chamber along either side thereof, great convenience results since the bedstead may thus be swung from the storage chamber into either one of two rooms or a room and a screened 45 perch provided on opposite sides of the storage chamber; thus making the same bed available alternatively in a plurality of sleeping spaces.

Other objects and advantages may appear 50 as the invention is unfolded in detail in the subjoined detail description and it is observed from such description taken in connection with the drawings filed herewith that the advantages derived are partly due 55 to the specific construction of the carrier members, partly due to the combination of elements forming the building structure, and also partly due to the combination of the particular carrier-device and the particular arrangement of elements of the building 60 structure.

The objects and advantages of the invention may more fully appear from the subjoined detail description.

65 The invention may be variously embodied.

The accompanying drawings illustrate the invention.

Figure 1 is a broken plan view of one embodiment of the invention, the building structure being shown in section. The bedstead is shown stored in solid lines and other consecutive or alternative positions of the bedstead are shown in broken lines. 70

Fig. 2 is an enlarged broken sectional elevation on line indicated by x^2-x^2 , Fig. 1, 75 the parts being in positions they occupy when the bedstead is unstored.

Fig. 3 is a detail partly in section on line indicated by x^3 , Figs. 1 and 2.

Fig. 4 is a plan view of an embodiment of 80 features of the invention, the building structure being shown in section. The stored position of the bedstead is indicated in solid lines and other consecutive or alternative positions of the bedstead are shown in 85 broken lines.

Fig. 5 is an enlarged fragmentary plan of the embodiment shown in Fig. 4, the same being in section on line indicated by x^5 , Fig. 6. Solid lines indicate positions of 90 parts when the bedstead is in unstored position and broken lines indicate consecutive positions of said parts when the bedstead is swung into storage.

Fig. 6 is a broken sectional elevation on 95 line indicated by x^6 , Figs. 4 and 5, the parts being in positions they occupy when the bedstead is unstored.

Fig. 7 is a fragmentary plan section analogous to Fig. 5, but with the parts near the 100 beginning of the latch engaging position.

Fig. 8 is a fragmentary sectional elevation on line indicated by x^8 , Figs. 5 and 7.

Fig. 9 is a perspective view of one of the interlocking latch members shown in the 105 preceding figures.

Arrows on the section lines of the various views indicate the direction of sight.

The storage space 1 in this instance is formed as a chamber formed in a building 110 structure and comprising a front side wall 2, rear side wall 3, end walls 4, 4'', floor 5 and ceiling 5''. The side wall 2 is a screen between the storage space 1 and the use space 41 and the wall 3 is a screen between the 115 storage space 1 and the use space 31 and around the edge of such screen a bedstead may be swung.

The floor and ceiling form sub and overhead supports and close the bottom and top 120 of the storage space.

View of the storage space 1 may be normally prevented by a closure of any well-known or desired construction as, for instance, an outwardly swinging door 6 which 125 is hung, as shown in the drawings, so that it will extend normal to the side walls 2, 3 to close an opening a between them; and a door 6'' may be hung so that it will extend in alinement with said wall to close an open- 130

ing a' that may be narrow as shown to form a doorway from the sleeping room 41. It is, of course, understood that the closures may be portières or sliding doors if desired, but 5 in the drawing only swinging doors are shown.

The storage space or chamber 1 may be used as an ordinary closet for holding clothing and the like, not shown, and is de- 10 signed to store a bedstead 7 constructed after any suitable design and capable of being stored within the space extending from end to end of the rear face of the front side wall 2, and, in other words, within the area 15 8 between a plane extending transversely of said wall 2 at the door-jamb 9 and the end wall 4, and said bedstead is pivotally mounted by a primary pivot formed by pins 10 and 11, to a swinging and laterally shift- 20 able carrier-device 12 adapted to swing the bedstead to and from said space and area so that the openings a , a' , if both are present, will permit of easy ingress to and egress from the storage space 1. It is understood 25 that either door 6, or 6'' may be omitted without having the storage space uncon- cealed.

The carrier-device 12 comprises upper and lower jointed members consisting of upper 30 and lower primary arms 13, 14, and upper and lower secondary arms 15, 16, the joint being formed by a vertical secondary pivot 17 which may be tubular or otherwise as de- 35 sired, and preferably connects said upper and lower members together.

The secondary arms are connected to one another by a vertical post or tertiary pivot 18 which may be tubular or otherwise as de- 40 sired and which is rotatably mounted by a step bearing that may be fixed to the floor 5 as at 19, Fig. 6, or that may be shiftable relative to said floor as at 19', Fig. 2, said step bearing being at a substantial distance from the door-jamb 9. The jointed mem- 45 bers and the bedstead are carried by the pivotal support thus formed.

In order that the pivotal mounting may be located at a substantial distance from the door-jamb 9, and at considerable distance 50 inside of the storage space 1, I have conceived of providing each of the primary arms 13, 14 with an elbow 20, so that the limbs 21 of the primary arms may extend transversely of the front wall 2 and so that 55 the limbs 22 of said arms may extend sub- stantially at right angles to the limbs 21 and along the door-jamb 9 or rear face of said front wall when the bedstead is out of storage, as in solid lines Figs. 2, 5 and 6. 60 It is thus seen that the bent primary arms 13, 14 may extend along and embrace two faces of the door-post, or edge of the screen- ing member or wall 2.

I have shown the secondary arms 15, 16 65 substantially straight but it is understood

that they may be provided with elbows if desired.

It is observed that when the bedstead is in the stored position designated A and shown by solid lines in Fig. 4, it may be 70 readily swung from the storage chamber 1 by simply pulling on the bedstead 7, the construction being such that the secondary pivot 17 is slightly to the rear of a line indicated at b passing through the primary 75 pivots 10, 11 and the post 18, there being a stop designed to deflect an intermediate joint 17 of the carrier member out of alignment with said pivots 10 and 18. Said stop may be of any suitable character as the wall 80 2 in Fig. 1, or the pin 24 mounted in the floor 5 in Fig. 4 and is designed to engage the joint of the lower carrier-member so that the primary and secondary arms 13, 15 above, and 14, 16 below, respectively will 85 jackknife and fold forward toward one another through positions B, C, until the joints of the carrier-members come to rest against a second stop which in this instance is formed by the face 25 of the jamb or front wall, the 90 parts then being in the positions designated D; and thereafter the primary arms alone will swing around the secondary pivot 17 and the bedstead may also be swung on its primary pivot 10, 11 to bring the parts to 95 the unstored positions designated E where the folding or upending section well known in the art may be lowered for use.

When the bedstead 7 is in the unstored solid line position designated E in Figs. 1, 100 4 and 5, it may be readily swung into the storage chamber 1 by pushing and turning the bedstead, the primary and secondary arms 13, 15 and 14, 16 respectively then jackknifing and folding forward toward one 105 another to the position designated F, thus bringing the joint of the lower carrier-member against the stop 24, whereupon further pressure against the bedstead swings the primary arms around the secondary pivot 110 17 to return the parts to the stored position A.

When the joints 17 of the carrier arms 13, 14, 15, 16 are against the face 25 any tendency of said joints to swing away from 115 said face may be entirely overcome by a suitable latch device illustrated in Figs. 4 to 9 but not necessary and for this purpose there is provided an automatic latch device comprising interlocking members 26, 27, the 120 member 26 being stationarily mounted on the jamb face 25 and the member 27 turning with the pivot 17 and preferably being formed integral with the lower primary arm 14.

The member 26 is provided with a semi-circular tongue 28 designed to engage a semi-circular groove 29 in the member 27, said tongue and groove being concentric with one another and the relative rotative 130

positions of the tongue and groove being such as to hold said tongue and groove in engagement when the parts are in the use position E, see Figs. 1, 4 and 5, and to continue to hold them in engagement while the arms 14, 13 swing from said position E to just short of position E' shown in Fig. 7, in which latter position E' the tongue and groove are disengaged so as to allow swinging 10 of the secondary arms 16, 15.

From the foregoing it is clear that as the primary arms 14, 13 swing about the pivot 17, the tongue and groove 28, 29 act automatically to latch and unlatch the secondary 15 arms 15, 16.

In Fig. 1 the rear side wall 3 is provided with an opening d which may be provided with a suitable closure as an inwardly swinging door 30 or the like; said second opening 20 being provided so that the bedstead 7 may be swung along the outer face of the wall 3 into a suitable space 31 which may be an ordinary room or may be a screened porch of which the screening is indicated at 32.

In order to swing the bedstead 7 to the space 31 through the opening d I have made provision whereby the carrier-members may be extended to greater lengths than required to swing the bedstead through the openings 25 a and a' and to effect this I connect the tertiary pivot 18 by upper and lower tertiary arms 33, 34 to a fourth pivot 35 that is rotatably mounted by a step bearing 36 or the like on the floor 5, and that carries the 30 jointed members 13, 15, 33, above and 14, 16, 34 below.

As it may be desirable at times to use only the primary and secondary arms to effect movement of the bedstead 7 through 40 positions corresponding to the different positions A, B, C, D, E, Fig. 4, and F Fig. 5 provision is made for holding the tertiary arms 33, 34 against movement so that the operation of the device in Fig. 1 may be 45 made to correspond with the operation of the device in Fig. 4, and for this purpose the swinging end of the upper tertiary arm 33 is provided with a tooth in the form of a pin 37 designed to be releasably engaged by 50 a latch hook 38 which is pivoted to a bracket 39 that is fastened to the rear face of the wall 2.

In Fig. 2 the pivot 35 and in Fig. 6 the pivot 18 are shown extending substantially 55 from the floor 5 to the ceiling 5" and the pivot in either case is held against tipping by a bracket, step or bearing 40 which may be bolted or otherwise fastened to the ceiling or other suitably located support.

From the foregoing it is clear that when 60 it is desired to unstore the bedstead 7 the operator will swing the bedstead from position A through successive positions B, C and D to the unstored position E as in Fig. 4, or that the operator will swing the bed-

stead from the deep stored position G where it is shown in solid lines in Fig. 1, through positions H and J to the unstored or use position E, when it is desired to use the bedstead in the room 41; or that the operator 70 may swing the bedstead from the stored position G, Fig. 1, through position K to the unstored reverse use position L when it is desired to use the bedstead in the space 31.

The operator may swing the bedstead 7 75 in Fig. 1 to the storage chamber 1 from position E to a position corresponding to the stored position A in Fig. 4 by first adjusting the latch hook 38 to engage the pin 37 to hold the pivot 18 against swinging, and then 80 operating the bedstead as hereinbefore described to swing the primary arms 13, 14 through a position corresponding to position E' Fig. 7 and position F Fig. 5 to said corresponding A position.

The bedstead may be pivoted on a horizontal pivot to open and close by any suitable means as, for instance, by the construction shown by my previous invention for wall beds, filed October 24, 1912, Serial No. 727,609, and as the construction of the horizontal pivoting means is immaterial to the 90 operation of this invention such means are not herein described or shown.

It is particularly pointed out that not 95 only can the bed be detracted to a position between the opening a and the end wall 4 but that the entire carrier-device 12 can be retracted to a considerable distance from the opening and that by the novel combination of the particular building structures and the particular carrier-devices, carrier arms of minimum length, say about nine inches, may be employed to effect perfect 100 concealment of the bedstead and carrier-device when stored.

Each of the arms 13, 14, 15, 16, 33 and 34 is of less length than the distance between the supporting pivot and the edge of the screen 2 past which the bed is adapted to 110 swing.

I claim:

1. The combination with a storage chamber having a door-jamb, of a bedstead, a primary arm pivoted to the bedstead and provided with an elbow permitting said arm to extend along two faces of the door-jamb, and a secondary arm pivoted to the primary arm and pivotally mounted in the storage chamber at a substantial distance 115 from said door-jamb, so that the bedstead may be carried by the primary arm from the storage chamber to a position for use and may be in such a position when the primary arm is extended along said two faces.

2. The combination with a building structure having a storage chamber provided with an opening, of a post pivotally mounted in the storage chamber at a substantial 120

distance from said opening, a secondary arm mounted on the post, a primary arm pivoted to the secondary arm and designed to extend transversely through said opening, and a bedstead pivoted to said primary arm.

3. The combination with the front and rear walls of a storage chamber, of a bedstead, and a carrier device pivotally supported within the storage chamber and designed to swing the bedstead from the outer face of one of said walls to the outer face of the other wall.

4. The combination with a structure forming a storage chamber, of a bedstead, and a carrier device pivotally supported within the storage chamber and designed to swing the bedstead from one position outside of the storage chamber to a reverse position outside of said chamber.

5. The combination with the walls of a storage chamber, of a bedstead; a carrier device pivotally supported within the storage chamber and pivotally connected with the bedstead, said carrier device being adapted to swing the bedstead from the storage chamber alternatively to a position for use outside of one of the walls or to a position for use outside of another of said walls.

6. The combination with the side walls of a storage chamber, of a bedstead, a primary arm pivoted to the bedstead, a secondary arm pivoted to the primary arm, a tertiary arm pivoted to the secondary arm, and a pivotal mounting for the tertiary arm between said walls, said arms and pivots adapting the bedstead to be swung from a position between the walls to a position for use outside of either of said walls.

7. The combination with a wall, of a bedstead, a jointed carrier member, a pivot connecting said carrier member to the bedstead, a pivotal mounting for the carrier member, and a stop designed to deflect the joint of the carrier-member out of alinement with said pivots when the carrier member is extended along said wall.

8. The combination with a storage chamber having an opening, of a bedstead, a carrier member having a joint and pivoted to the bedstead, a pivotal mounting for the carrier member inside of the storage chamber, and means forming a stop for the joint

at the margin of the opening so that the bedstead will swing around said joint.

9. The combination with a storage chamber having an opening, of a bedstead, a carrier member having a joint and pivoted to the bedstead, a pivotal mounting for the carrier member inside of the storage chamber, means forming a stop for the joint at the margin of the opening, and means operable by movement of the carrier member to latch the joint against movement away from said stop as the bedstead swings around said joint.

10. A wall bed comprising a bedstead, a carrier device connected to the bedstead and formed of primary and secondary arms pivoted to one another, a pivotal mounting for the secondary arm, a stationarily mounted latch member, and another latch member on the primary arm designed to engage said stationary latch member to prevent swinging of the secondary arm when the primary arm is swung relative to said secondary arm.

11. A wall bed comprising a bedstead, a carrier device connected to the bedstead and formed of primary and secondary arms pivoted to one another, said primary arm being provided with a curved groove, a pivotal mounting for the secondary arm, and a stationarily mounted bracket having a curved tongue to engage said groove while the primary arm turns relative to the secondary arm.

12. In combination, a primary arm, a secondary arm pivoted to the primary arm, a bedstead hung on the primary arm, and a shiftable step bearing supporting the pivot.

13. In combination, a primary arm, a secondary arm pivoted to the primary arm, a bedstead hung on the primary arm, a tertiary arm pivoted to the secondary arm, a caster to shiftable support the pivot connecting the tertiary and secondary arms to one another, and a pivotal mounting for the tertiary arm.

In testimony whereof, I have hereunto set my hand at Los Angeles, California, this 15th day of November, 1913.

WILLARD C. JAMES.

In presence of—

JAMES R. TOWNSEND,
GEORGE H. HILES.
